UNITED STATES PATENT OFFICE.

ADOLF K. F. HARNAPP, OF WEST NEW YORK, NEW JERSEY.

DESIGN FOR A SCARF.

Application filed October 10, 1928. Serial No. 28,422. Term of patent 3½ years.

To all whom it may concern:

Be it known that I, ADOLF K. F. HARNAPP, a citizen of the United States, residing at West New York, county of Hudson, and State of New Jersey, have invented a certain new, original, and ornamental Design for a Scarf, of which the following is a specification, reference being had to the accompanying drawing, forming part thereof.

The figure is a plan view of one end of a scarf constituting my new design, the opposite end being a repetition.

I claim:

The ornamental design for a scarf, as shown and described.

ADOLF K. F. HARNAPP.
